FURNITURE ARM TRAY

Albert T. Hansen, 1042 Harrison Ave.,
Lincoln, Calif. 95648

Filed Aug. 6, 1968, Ser. No. 13,047

Term of patent 3½ years

Int. Cl. D6—01

U.S. Cl. D33—14

FIG. 1

FIG. 3

FIG. 1 is a perspective view of my new design for a furniture arm tray;

FIG. 2 is a bottom plan view thereof; and

FIG. 3 is an end elevational view thereof as viewed from the right as seen in FIG. 1.

I claim:

The ornamental design for a furniture arm tray, substantially as shown.
